UNITED STATES PATENT OFFICE

147,622

DESIGN FOR A REFRIGERATED DISPLAY CASE

John G. Rideout, Chagrin Falls, Ohio

Application April 22, 1946, Serial No. 128,856

Term of patent 3½ years

(Cl. D80—11)

To all whom it may concern:

Be it known that I, John G. Rideout, a citizen of the United States and a resident of Chagrin Falls, Cuyahoga County, Ohio, have invented a new, original, and ornamental Design for a Refrigerated Display Case, of which the following is a specification, reference being had to the accompanying drawing, forming a part thereof.

In the drawing:

The figure is a front perspective view of the refrigerated display case showing my new design.

I claim:

The ornamental design for a refrigerated display case, as shown.

JOHN G. RIDEOUT.
